UNITED STATES PATENT OFFICE

2,206,193

EXHAUST DEVICE FOR EXPLOSION OR
INTERNAL COMBUSTION ENGINES

Michel Kadenacy, Paris, France

Original application August 1, 1934, Serial No. 738,016, now Patent No. 2,110,986, dated March 15, 1938. Divided and this application February 3, 1938, Serial No. 188,555. In Great Britain December 13, 1933

11 Claims. (Cl. 60—32)

The applicant has found that in an internal combustion engine, the behaviour of the gases is such as to lead to the conclusion that as a consequence of the combustion of the charge, and while still in the cylinder, the burnt gases form a mass having a high initial velocity and possessing properties similar to those of a resilient body, so that when the exhaust orifice opens this mass seeks to project itself bodily from the cylinder and to leave the latter in a consequent vacuous condition.

The present invention relates to two-stroke cycle internal combustion engines, wherein at least a substantial portion of the burnt gases leaves the cylinder at a speed much higher than that obtaining when a flow resulting from an adiabatic expansion only is involved and in such a short interval of time that it is discharged as a mass, leaving a depression behind it which is utilised in introducing a fresh charge into the cylinder.

The applicant has also found that in the operation of such an internal combustion engine the burnt gases do not leave the cylinder immediately the exhaust orifice commences to open. There is first a period of delay, during which the burnt gases do not issue from the cylinder, and after this delay has elapsed the burnt gases issue bodily from the cylinder with an extremely high velocity as a mass which responds to the laws of reflection and rebound and it leaves in the cylinder a profound depression. Subsequently, this outward motion of the burnt gases is reversed in direction and if the gases are allowed to re-enter the cylinder they destroy the depression left therein.

In the specification of U. S. Patent No. 2,102,559 issued December 14, 1937, the applicant has described and claimed a method of charging two-stroke cycle internal combustion engines which consists in opening the inlet orifice for the introduction of a fresh charge after the exhaust orifice opens, but only with the required delay to ensure that the burnt gases are then moving outwardly through the exhaust system as a consequence of their mass exit from the cylinder and cause a suction effect to be exerted in the cylinder at the said inlet orifice.

In such an engine, an untimely return of the burnt gases may have an objectionable influence on the contents of the cylinder and the object of the present invention, which object is also that of the invention described in the applicant's U. S. Patent No. 2,110,986, issued March 15, 1938, from which the present application has been di-

vided, is to provide in the exhaust system of an engine operating in accordance with the above method, means which are adapted to permit the free exit of the mass of burnt gases from the cylinder and to prevent the return of this mass or a portion thereof of burnt gases to the cylinder by utilising the above mentioned properties of the burnt gases.

The invention consists in the provision within the exhaust system of deflecting means situated between the exhaust orifice and the zone in the exhaust system from which the return of the burnt gases occurs after the said bodily exit from the cylinder at high velocity, the said deflecting means being adapted to permit the free outward movement of the burnt gases and to prevent by reflection the return of the said gases to the cylinder.

It is to be understood that in considering the free discharge of the burnt gases losses due to friction are excepted, but these losses should of course be kept down to a minimum.

Now if the characteristics of the exhaust system are fixed, the interval elapsing between the bodily exit of the burnt gases from the cylinder and the subsequent reversal in direction of movement of these gases is a duration of time which is substantially constant. As a consequence, this interval will extend over a larger crank angle at high engine speeds than at low engine speeds. Consequently the return of the burnt gases is more liable to exert an objectionable influence on the contents of the cylinder at low engine speeds. If the angular separation between exhaust opening and inlet opening is also fixed, there will be a limiting low speed for which the return occurs too soon to permit the timing of inlet opening to be operative in the required manner.

In general, therefore, the means according to the invention will have the effect of improving the operation of the engine at low engine speeds and of extending the possible range of working speeds of the engine in the direction of low speeds.

In one embodiment of the invention the said deflecting means comprise surfaces adapted to impart a whirling motion to the whole of the issuing mass of burnt gases so that they cannot return to the cylinder, or to a portion only of the issuing mass, while allowing the free passage of the remainder of the said burnt gases, so as to form a gaseous plug adapted to cause any subsequent return wave of the said burnt gases to

rebound without further appreciable loss in velocity in the direction of exhaust.

When the body of burnt gases after its return towards the cylinder from the atmosphere it has encountered, is caused to rebound again in the direction of exhaust by the device according to the invention, the body of gases thereby produces an additional suction effect which is capable of further improving the scavenging and 10 charging of the cylinder.

According to a further feature of the invention the distribution is arranged so that the inlet closes with a sufficient retardation to ensure that the cylinder will be fully charged and that any 15 loss of charge, through the exhaust duct due to this additional suction effect will be compensated.

Preferably the said deflecting surfaces will be situated close to the cylinder, since the zone from which the body of gases issuing from the 20 cylinder returns is itself situated very near the exhaust orifice of the cylinder, and the device must be situated between the exhaust orifice and this zone before it can exert its action in preventing the return of the burnt gases to the 25 cylinder.

When the engine is first started and until it has acquired sufficient speed air may be blown into the cylinder as described in the above mentioned U. S. Patent No. 2,102,559.

30 In the drawings:

Figure 1 is a view in partial section of a first embodiment.

Figure 2 is a view in axial section, on a larger scale, of the exhaust device of this embodiment, taken on the line 2—2 in Figure 1.

Figure 3 shows a modified form of the exhaust device.

Figure 4 shows another modified form of exhaust device.

40 In Figures 2, 3 and 4 the arrows indicate the displacement of the gases during their outward and returning or whirling movement at high speed. The arrows in full lines indicate forward movement, and the arrows in dot and dash lines indicate return movement.

45 By way of example and with reference to Figure 1, it is assumed that the invention is applied to an engine having a cylinder 1, in which slides a piston 2, actuating the crank shaft through the medium of a connecting rod 3. 4 is the inlet duct, and 5 the inlet valve controlled for instance by a push rod and rocker arm 6, to open in the required manner.

50 The exhaust duct 7 opens to the cylinder through one or more ports 8 uncovered by the piston 2 when it approaches bottom dead centre.

55 This engine may be of the explosion type, in which case it will be fed through the duct 4 with carburetted mixture, or it may be of the compression ignition type, in which case it will be fed with air through the duct 4 and with fuel through an injector 49.

60 In this figure it is assumed that the deflecting surfaces, which, according to the invention are arranged or formed in the exhaust duct, are situated closely adjacent the cylinder in a portion 71 of the latter.

65 The axis 2—2 of the exhaust duct is preferably set downwardly so that it forms a relatively acute angle α with the axis Y—Y of the cylinder, as shown in the figure. More generally, the exhaust duct will be so set relatively to the cylinder, as to impart the smallest possible change of 70 direction to the burnt gases issuing from the

cylinder, that is to say, to check them as little as possible.

The internal construction of the portion 7' of the exhaust duct is shown in section in Figure 2.

75 The inner wall of the duct 7 comprises a 5 toroidal cavity 9, opposite which is arranged a deflector member 10, situated upon the axis 2—2.

This deflector has a conical portion 10a, the apex of which faces the cylinder 1 and the surface of this cone is so set as to guide the burnt gases, when they issue from the cylinder, towards the torus 9, as shown by the arrows F₁.

10 The gases guided by the inner wall of the torus, as well as by a portion 10b of the deflector 10 which completes this torus are trapped within the torus and whirl in the direction of the arrows F₂ and form an obturating plug.

15 When the whirling movement comes to an end, the gases issue to the exterior through a free 20 space 11 existing between the deflector 10 and the edge of the torus 9.

25 After this whirling mass has been formed by the initial portion of the gases the following portion can also pass directly through the space 11 without entering the torus 9, by following the path indicated by the arrows F₃. This portion returns in the direction F₁', whereupon it encounters the downside end of the deflector 10 which is formed, as indicated at 10c, for deflecting 30 the returning mass into the torus 9 in the direction F₂'.

35 This returning fraction of the gases then encounters the plug formed by the whirling mass at F₂'. It is thereby prevented from returning to the cylinder and rebounds from this plug in the direction of exhaust.

40 Figure 3 illustrates a modification comprising, in the wall of the exhaust duct, a torus 9 similar to that in the form of construction previously described, and opposite this torus, a deflector 12 constituting two walls 12a, 12b, which 45 also guide the gases in the directions F₁—F₂.

45 The difference relative to the preceding form of construction resides in the fact that the downside end of the deflector is shaped, at 12c, as a portion of a torus, so as to trap the gases which have passed the torus 9 in the direction F₃ and have returned in the direction F₁', and to cause 50 them to form a second plug F₃', or again to send them, in the direction F₄, tangentially to the first whirling plug so that they reinforce the latter instead of running the risk of destroying it, as in the first embodiment in which they encounter the whirling mass radially.

55 In the modification illustrated in Figure 4, the torus 9 formed by the inner wall of the exhaust duct, terminates, on the downside, in a conical incline 13.

60 The deflector 14, has, on the upside, two parts 14a—14b which deflect the gases in the directions F₁—F₂, so as to form a whirling plug as described. On the downside, it has a part 14c parallel, or nearly parallel, to the wall 13.

65 Under these conditions, the fraction of the gases which has escaped as shown by F₃ and has returned in the direction F₁', is guided between the two walls 14c—13, in the direction F₅', so as to enter the torus 9 tangentially and to form 70 an eddy F₆ which is added to the eddy F₂ and reinforces the obturating plug formed by the whirling mass.

75 In these embodiments, a gaseous obturating plug is formed by a whirling motion imparted

to the totality of or a portion of the burnt gases during their forward movement.

In the above examples, one cylinder only has been considered, but any suitable arrangements may of course be provided for rendering the invention application to a multi-cylinder engine.

I claim:

1. Method of controlling two-stroke cycle internal combustion engines, which comprises establishing communication between the cylinder and exhaust system during the firing stroke, providing for the issuance of the burnt gases from the cylinder substantially as a mass in an interval of time shorter than that which would be required for the burnt gases to expand down to the ambient pressure by adiabatic flow, whereby the mass of gases moves outward and thereafter returns, permitting the free and unrestricted outward motion of the issuing mass of burnt gases, maintaining the admission orifice closed until the said issuance of the mass of burnt gases is in full progress, admitting fresh charge into the cylinder when the said issuance of the burnt gases is in full progress and causes a suction effect to be exerted in the cylinder, while the exhaust port is still open, and imparting a whirling motion to the issuing mass of burnt gases before it reaches the zone from which the return of the burnt gases would occur, whereby the return of the burnt gases to the cylinder is hindered.

2. Method of controlling two-stroke cycle internal combustion engines, which comprises establishing communication between the cylinder and exhaust system during the firing stroke, providing for the issuance of the burnt gases from the cylinder substantially as a mass in an interval of time shorter than that which would be required for the burnt gases to expand down to the ambient pressure by adiabatic flow, whereby the mass of gases moves outward and thereafter returns, permitting the free and unrestricted outward motion of the issuing mass of burnt gases, maintaining the admission orifice closed until the said issuance of the mass of burnt gases is in full progress, admitting fresh charge into the cylinder when the said issuance of the burnt gases is in full progress and causes a suction effect to be exerted in the cylinder, while the exhaust port is still open, imparting a whirling motion to a portion of the issuing mass of burnt gases before said mass reaches the zone from which the return of the burnt gases would occur, and permitting the free and unrestricted outward motion of the remaining portion of the mass of burnt gases to the limit of its outward travel, whereby the latter portion thereafter returns towards the cylinder and rebounds from said whirling portion without appreciable loss in velocity in the direction of exhaust.

3. Method as claimed in claim 2 including imparting a whirling motion to the second mentioned portion of the mass of burnt gases on its return motion.

4. In a two-stroke cycle internal combustion engine having an exhaust conduit, wherein the burnt gases are discharged from the cylinder into the exhaust conduit substantially as a mass in an interval of time shorter than that which would be required for the burnt gases to expand down to the ambient pressure by adiabatic flow, whereby the said mass moves outwardly and thereafter returns, the said exhaust conduit providing a free passage for the burnt gases to the limit of outward travel of said mass, and wherein

an inlet is opened for the introduction of fresh charge into the cylinder while the exhaust port is still open, and when the said issuance of the burnt gases is in full progress and causes a suction effect to be exerted in the cylinder, the provision of means in the exhaust conduit for imparting a whirling motion to the issuing mass of burnt gases before it reaches the zone from which the return would occur, whereby the return of the burnt gases to the cylinder is hindered.

5. In a two-stroke cycle internal combustion engine having an exhaust conduit, wherein the burnt gases are discharged from the cylinder into the exhaust conduit substantially as a mass in an interval of time shorter than that which would be required for the burnt gases to expand down to the ambient pressure by adiabatic flow, whereby the said mass moves outwardly and thereafter returns, the said exhaust conduit providing a free passage for the burnt gases to the limit of outward travel of said mass, and wherein an inlet is opened for the introduction of fresh charge into the cylinder while the exhaust port is still open and when the said issuance of the burnt gases is in full progress and causes a suction effect to be exerted in the cylinder, the provision of means in the exhaust conduit for imparting a whirling motion to a portion of the issuing mass of burnt gases before said mass reaches the zone from which the return of the burnt gases would occur, and permitting the free and unrestricted outward motion of the remaining portion of the mass of burnt gases to the limit of its outward travel, whereby the latter portion thereafter returns towards the cylinder and rebounds from said whirling portion without appreciable loss in velocity in the direction of exhaust.

6. In a two-stroke cycle internal combustion engine having a cylinder, a crank shaft, a piston moving in this cylinder and connected to said crank shaft, inlet and exhaust orifices on the cylinder for introducing fresh charge and for discharging the products of combustion respectively, and wherein for recharging the cylinder the burnt gases are allowed to leave the cylinder substantially as a mass in an interval of time shorter than that which would be required for the burnt gases to expand down to the ambient pressure by adiabatic flow, whereby the said mass moves outwardly and thereafter returns and the fresh charge is allowed to enter the cylinder when the issuance of the burnt gases is in full progress and causes a suction effect to be exerted at the inlet orifice, and while the exhaust port is still open, an exhaust conduit leading from said exhaust orifice, a toroidal cavity in said exhaust conduit adjacent the cylinder and a deflector body within said exhaust conduit arranged to direct the issuing mass of burnt gases tangentially into said cavity, whereby a whirling gaseous plug consisting of at least a portion of the issuing mass of burnt gases is formed in said toroidal cavity before the said gases reach the zone from which the return would occur whereby the return of the burnt gases to cylinder is hindered.

7. In a two-stroke cycle internal combustion engine having a cylinder, a crank shaft, a piston moving in this cylinder and connected to said crank shaft, inlet and exhaust orifices on the cylinder for introducing fresh charge and for discharging the products of combustion respectively, and wherein for recharging the cylinder the burnt gases are allowed to leave the cylinder substantially as a mass in an interval of time

shorter than that which would be required for the burnt gases to expand down to the ambient pressure by adiabatic flow, whereby the said mass moves outwardly and thereafter returns and the
5 fresh charge is allowed to enter the cylinder when the issuance of the burnt gases is in full progress and causes a suction effect to be exerted at the inlet orifice, and while the exhaust port is still open, an exhaust conduit leading from
10 said exhaust orifice, a toroidal cavity in said exhaust conduit adjacent the cylinder and a deflector body within said exhaust conduit arranged to direct the issuing mass of burnt gases tangentially into said cavity, whereby a whirling gaseous
15 plug consisting of at least a portion of the issuing mass of burnt gases is formed in said toroidal cavity before the said gases reach the zone from which the return would occur, and arranged to deflect any returning burnt gases tangentially into
20 said cavity whereby the return of the burnt gases to cylinder is hindered.

8. In a two-stroke cycle internal combustion engine having a cylinder, a crank shaft, a piston moving in this cylinder and connected to said
25 crank shaft, inlet and exhaust orifices on the cylinder for introducing fresh charge and for discharging the products of combustion respectively, and wherein for recharging the cylinder the burnt gases are allowed to leave the cylinder
30 substantially as a mass in an interval of time shorter than that which would be required for the burnt gases to expand down to the ambient pressure by adiabatic flow, whereby the said mass moves outwardly and thereafter returns and the

fresh charge is allowed to enter the cylinder when the issuance of the burnt gases is in full progress and causes a suction effect to be exerted at the inlet orifice, and while the exhaust port is still open, an exhaust conduit leading from said exhaust orifice, a toroidal cavity in said exhaust conduit adjacent the cylinder and a deflector body within said exhaust conduit arranged to direct the issuing mass of burnt gases tangentially into said cavity, whereby a whirling gaseous 10 plug consisting of at least a portion of the issuing mass of burnt gases is formed in said toroidal cavity before the said gases reach the zone from which the return would occur, and arranged to deflect any returning burnt gases radially into 15 said cavity whereby the return of the burnt gases to cylinder is hindered.

9. The combination as claimed in claim 7, wherein the deflector body is in the form of two cones with their bases in contact. 20

10. The combination as claimed in claim 8, wherein the deflector body is in the form of two cones with their bases in contact.

11. The combination as claimed in claim 6, wherein the deflector body has a progressively 25 decreasing configuration in the direction of the engine cylinder and is provided with a toroidal cavity directed away from the cylinder, whereby any returning burnt gases form a whirling gaseous plug in said toroidal cavity in the deflector 30 body and are then directed tangentially into the toroidal cavity in the exhaust conduit.

MICHEL KADENACY.
